CLAIM

The ornamental design for a star drag component, as shown and described.

DESCRIPTION

FIG. 1 is a front isometric view of a fishing reel that includes the star drag component. The reel forms no part of the claimed design and is shown for reference purposes only. FIG. 2 is a back isometric view of the star drag component. FIG. 3 is a front view of the star drag component of FIG. 1. FIG. 4 is a back view of the star drag component of FIG. 1. FIG. 5 is a left side view of the star drag component of FIG. 1; and,

FIG. 6 is a right side view of the star drag component of FIG. 1.

The star drag component is substantially symmetrical about the center and thus the top and bottom views are omitted. The broken line portions of the drawings are for illustrative purposes only and form no part of the claimed design.

1 Claim, 5 Drawing Sheets
